Geo. E. Hart, by

Arnoldus Russell, his Atty.

UNITED STATES PATENT OFFICE.

GEORGE E. HART, OF WATERBURY, CONNECTICUT, ASSIGNOR TO THE
WATERBURY WATCH COMPANY, OF SAME PLACE.

MANUFACTURE OF WATCH-BALANCES.

SPECIFICATION forming part of Letters Patent No. 364,107, dated May 31, 1887.

Application filed July 22, 1886. Serial No. 208,759. (No model.)

To all whom it may concern:

Be it known that I, GEORGE E. HART, of Waterbury, in the county of New Haven, and in the State of Connecticut, have invented certain new and useful Improvements in the Manufacture of Watch-Balances; and I do hereby declare that the following is a full, clear, and exact description thereof, reference being had to the accompanying drawings, in which—
10 Figure 1 is a perspective view of the blank from which my balance is made as cut from a sheet of metal. Fig. 2 is a like view of the same after having one of its faces recessed. Fig. 3 is a perspective view of said blank 15 after having passed through the forming-dies. Fig. 4 is a like view of the same after the fin has been trimmed from around its periphery. Fig. 5 is a perspective view of said blank 20 after the surplus metal has been trimmed from its central portion. Fig. 6 is a like view of the same after having been re-pressed, and Fig. 7 is a perspective view of the completed blank.

Letters of like name and kind refer to like 25 parts in each of the figures.

The design of my invention is to enable watch-balances to be more easily and quickly made than has heretofore been practicable; and to this end it consists, principally, in the 30 method employed for blanking out a watch-balance, substantially as and for the purpose hereinafter specified.

It consists, further, in the method employed for blanking out and completing a watch-balance, substantially as and for the purpose 35 hereinafter shown.

In the carrying of my invention into practice, a disk, A, is cut from a sheet of metal, and a circular recess, a, is then cut within one of its 40 sides by any suitable tool. The blank A is next subjected to the action of two dies, one of which dies has a plain face, while within the face of the other die is formed a recess that corresponds in size and shape to the like features of the proposed balance-wheel, the result being, as shown in Fig. 3, the production in relief upon the recessed side of said blank 45 of the rim a' and peripheral projections a'',

which resemble the screws of an expansion balance-wheel. The blank A is next submitted to the action of trimming-dies, which remove the surplus metal or fin from around its periphery and leave it in the shape seen in Fig. 4, after which other trimming-dies cut from within its rim all of the metal except 55 such as forms the central arm, a³, as shown in Fig. 5. The next operation consists in subjecting the blank A to the action of dies which correspond to those first used and operate to give a perfect form to each portion of 60 said blank, and to compress and render dense the metal of the same, the result being shown in Fig. 6. The final operation consists in rendering the inner and outer edges of the blank A perfectly smooth by shaving from the 65 same with suitable dies any surplus stock in the shape of a fin, which leaves said blank in the form shown in Fig. 7, ready to be completed by the formation of a central opening for the reception of a staff.

The balance-wheel thus produced has a perfect shape, and if properly placed upon a staff will run perfectly true. Its density so much exceeds that of ordinary metal that there is 75 much less expansion and contraction under variations of temperature than in balances of usual construction, and its cost is but a fraction of that heretofore required for the production of solid balances.

Having thus described my invention, what 80 I claim is—

1. The method employed for blanking out watch-balances, which consists in impressing the general form of the rim and peripheral projections of a balance upon a disk of metal 85 by means of a forging-die, and then forming the central arm and removing the surplus metal from the inner and outer peripheries of said rim by means of a cutting-die, substantially as and for the purpose specified.

2. The method employed for forming watch-balances, which consists in impressing the general form of the rim and peripheral projections of a balance upon a disk of metal by 95 means of a forging-die, then forming the central arm and removing the surplus metal from

the outer and inner peripheries of said rim by means of a cutting-die, and, lastly, subjecting the wheel thus formed to the action of a forging-die that is provided with a recess which 5 corresponds to the size and shape of the finished balance, substantially as and for the purpose shown.

In testimony that I claim the foregoing I have hereunto set my hand this 18th day of May, A. D. 1886.

GEORGE E. HART.
